CRUMB SWEEPER

Filed April 7, 1950

FIG. 1

UNITED STATES PATENT OFFICE

2,691,181

CRUMB SWEEPER

Walter Van Guilder, River Forest, Ill., assignor to
General Mills, Inc., a corporation of Delaware

Application April 7, 1950, Serial No. 154,463

4 Claims. (Cl. 15—22)

1

The present application relates to crumb sweepers for household use, and more particularly to an improved crumb sweeper having self-contained power means.

Various devices have been proposed in the past for removal of crumbs from a tablecloth or other surface. Some of these devices have been in the nature of mere scrapers, which are adapted to scrape or brush the crumbs toward the edge of the surface for collection in a napkin or container. Other devices have been of the "carpet sweeper" type in which a crumb brush is rotated in response to movement of the device across the surface.

The present invention relates to crumb sweepers of the movable brush type and it is one object of the invention to provide an improved combination and arrangement of parts in such a crumb sweeper.

Another object is the provision of self-contained power means for a crumb sweeper of the movable brush type.

Still another object is the provision of a crumb sweeper having self-contained power means in combination with means for setting and releasing the power means for controlled rotation of the brush.

Another object is the provision of a relatively simple combination in which the brush is readily removable for cleaning.

Other objects and advantages will be apparent from the following specification, in which a preferred embodiment of the invention is described.

In the drawings forming a part of this application,

Figure 1 is a side elevation of a crumb sweeper according to the invention, with certain portions broken away and other portions shown in section for clearness.

Fig. 2 is a partial perspective view, with certain portions broken away, showing details of the handle construction and the power means of the device of Fig. 1.

Fig. 3 is a sectional view on the line 3—3 of Fig. 1, and

Fig. 4 is a sectional view on the line 4—4 of Fig. 1.

As shown in Figs. 1, 3, and 4, the crumb sweeper according to the present invention includes a crumb-receiving body designated generally at 10. This body portion includes spaced end walls 12 and 14 between which a main outer wall 16 extends. Wall 16 serves as a front, top, and rear wall for the device and extends from a beaded forward edge 18 spaced somewhat above the bottom of the device to a bottom rear corner 55.

20 to provide a suitable housing for the rotatable brush, as well as a suitable receptacle for the crumbs to be collected.

This main body portion is relatively long and 5 narrow and includes an upwardly and rearwardly inclined partition member 22 extending horizontally from end wall 12 to end wall 14. Partition member 22 may be secured to the end walls in any desired fashion. As shown in the drawings, partition 22 has a substantially horizontal edge 24 extending from end to end and serving as a stop for the movable bottom 34 described below.

At one end of partition 22, a flange 26 is riveted 15 at 28 to the end wall 12. At the other end of partition 22 a similar flange 30 is riveted at 32 to the end wall 14 of the crumb-receiving body.

This body portion is provided with a bottom plate 34 which extends from the rear corner 20 20 outwardly past the edge 24 of horizontal partition 22 to provide a crumb-receiving receptacle portion or chamber 35 between the lower rear portion of wall 16, the partition 22, and bottom 34. This chamber 35 is designed for receipt of 25 the crumbs to be collected and is provided with a movable door through which the collected crumbs may be readily removed.

For convenience, in this particular embodiment of the invention, the bottom plate 34 also serves as the movable door and is pivoted on a 30 shaft 36 extending from end to end of the device at the lower rear corner thereof. A spring 38 has one end 40 engaging the bottom plate or door 34 and urging it upwardly against the edge 24 of partition 22. The other end of spring 38 is secured at 42 to the rear lower portion of wall 16.

The forward edge 44 of bottom plate 34 is designed to serve as a scraper edge for engagement with the surface of the material to be cleaned, as shown in Fig. 3.

Cooperating with this scraping edge 44 is a rotatable brush indicated generally at 46. This brush includes a main shaft portion 48 and radially projecting bristles 50. One end of the shaft or body portion 48 is provided with an extension 52 of reduced diameter. An annular shoulder 53 is thus formed at the point where this extension 52 projects from the brush shaft 48. The projecting end 52 of the brush is removably mounted in a slot between the forked ends 54 of a bearing bracket 56. Bearing bracket 56 is located near end wall 12 of the device and includes a flange 58 riveted at 60 to the top of body portion 16.

In order to retain the bearing extension 52 of

the brush in position between the bifurcated ends 54 of bearing member 56, a resilient retaining member 62 is provided. This retaining member or spring 62 has a horizontal portion 64 designed to engage just below the bearing extension 52 when the brush is in the heavy line position of Fig. 1. Retaining spring 62 is also provided with a tapered end 66 which serves both as a finger piece to release the bearing extension 52 and permit its downward removal from bearing bracket 56, and also as a convenient cam for retraction of the horizontal portion 64 of spring 62 as the bearing extension 52 is reinserted into the bracket 56. This retaining spring 62 also has a projecting flange 68 secured to the top of wall portion 16 by the same rivets 60 which hold the flange 58 of bearing member 56 in position.

At its other end, the brush 46 is provided with a rectangular bearing extension 70 designed for removable driven engagement with a tapered rectangular slot 72 in the end portion 74 of a suitable power shaft 76. The provision of the axially tapered slot 72, the inner or smaller end of which has the same cross section as the end of the rectangular bearing extensions 70 on brush 46, facilitates insertion and removal of the brush 46 and at the same time provides a positive driving engagement between the shaft 76 and brush 46 when the brush is in the heavy line position of Fig. 1.

In the preferred form of the invention shown in the drawings, the power shaft 76 is located within a handle portion 78 which extends or projects outwardly from the end wall 14 of the crumb sweeper along the axis of rotation of the brush 46. In the particular form shown, the axis of rotation of brush 46 is inclined upwardly in order that the handle portion 78 will have greater clearance above the top of the surface to be cleaned. Because of this upward inclination of the axis of the brush, a conical brush is employed, and the crumb-receiving body portion 10 of the device is correspondingly tapered from the narrow or lower end 12 to the broader or upper end 14.

Handle portion 78 has a projecting flange 80 at its inner end spaced outwardly from end wall 14 and substantially parallel thereto to provide a chamber for the latch and latch release mechanism to be described. This radial flange 80 of the handle portion has an inwardly directed or axial cylindrical rim 82 terminating in an outwardly directed flange 84 riveted to the end wall 14 at 86. The outer end of handle 78 has an inwardly directed flange or end wall 88 serving as a bearing for one end of the power shaft 76, the other end of power shaft 76 being journaled in end wall 14. A winding knob 90 is connected to the outer end of power shaft 76 and provides a convenient means for tensioning the power spring 92 which is mounted concentrically on power shaft 76. The outer end of power spring 92 is fastened to a hub or bearing portion 94 of the shaft 76 at 96 in order that this end of spring 92 will always move with the shaft 76. The other or inner end of power spring 92 is secured at 98 to the flange 80 of the handle portion. Thus rotation of the winding knob 90 and shaft 76 in the direction of the winding arrow shown in Fig. 2 will rotate the outer end 96 of the power spring 92 while the inner end 98 remains fixed in position. This winding movement will accordingly tension the power spring.

In order to retain the power shaft 76 and spring 92 in tensioned position, the power shaft is provided with a ratchet 100 engaged by the hook 102 of a latch or pawl member 104 pivoted at 106 to

the flange 80. A spring 108 normally urges the pawl 104 in a clockwise direction as viewed in Fig. 2 in order to latch the ratchet 100, power shaft 76, and power spring 92 in position.

In order to release the power means to obtain the desired rotation of brush 46, a release lever 110 is pivoted at 112 to flange 80 and includes an end 114 engaged beneath a lateral projection 116 on latch member 104. The other end of lever 110 is bifurcated as shown at 118 and is secured by a pin 120 to a release plunger 122. Release plunger 122 has a portion of reduced diameter 124 projecting upwardly through the annular rim 82 of the handle portion and carries a button or finger piece 126 at its upper end for convenient manipulation by the thumb or finger of the operator. The shoulder 128 between the portion 124 of reduced diameter and the main body portion 122 of the plunger serves as a stop to limit upward movement of the release plunger.

When the release button or member 126 is depressed by the user, the latch member 104 will be rotated against the tension of spring 108 to release the ratchet wheel 100 and permit rotation of the power shaft 76 and brush 46.

The operation of the crumb sweeper described above is extremely simple and convenient. The self-contained spring power means of the crumb sweeper can be readily wound in advance of the desired operation by rotation of knob 90. The device can then be moved across the surface to be cleaned in the direction indicated by the arrow 130 in Fig. 3 while the release member 126 is depressed to cause rotation of the brush and collection of the crumbs in the chamber 35 of the body portion. The device is particularly useful in removal of crumbs from the narrow areas between plates and other table utensils since the self-contained power mechanism permits rotation of the brush even though the crumb sweeper as a whole is held stationary with respect to the surface to be cleaned. Thus the relatively long narrow brush can be placed between obstacles and the brush can be rotated to remove crumbs from the area without the necessity of removal of such obstacles from the surface.

The particular arrangement and location of the parts, and particularly the location of a spring power means in the handle portion, permits the use of a relatively long-running spring and provides a compact and convenient structure.

Since minor variations and changes in the exact details of construction will be apparent to persons skilled in this field, it is intended that this invention shall cover all such changes and modifications as fall within the spirit and scope of the attached claims.

Now, therefore, I claim:

1. A crumb sweeper comprising a relatively long narrow crumb receiving body provided with a flat scraping edge for engagement with a surface to be cleaned, a relatively long narrow rotary brush mounted in the body for rotation on a predetermined axis, the brush having an outer edge parallel to said scraping edge and adjacent thereto, a handle on said body projecting from one end thereof along said predetermined axis, and spring power means in said handle operatively connected to the brush, said spring power means including a rotatable shaft extending along said axis within the handle, the shaft having inner and outer ends with the inner end directly engaging and driving the brush, a winding knob at the outer end of the handle rigidly connected to the shaft to 70 rotate the shaft and be rotated thereby, a spring

coiled around said shaft within the handle and having one end secured to the shaft and the other end secured to a stationary part of the sweeper, ratchet means on the shaft, a pawl cooperating with the ratchet means to lock the shaft against reverse rotation when the knob and shaft are rotated to wind the spring, and manually operable means for releasing said pawl.

2. A crumb sweeper comprising a relatively long narrow crumb receiving body provided with a flat scraping edge for engagement with a surface to be cleaned, a relatively long narrow conical rotary brush mounted in the body for rotation on an upwardly inclined axis, with the brush having an outer edge parallel to said scraping edge and adjacent thereto, a handle on said body projecting at an upward inclination from one end thereof along said upwardly inclined axis, and spring power means mounted and concealed within said handle and operatively connected to the brush.

3. A crumb sweeper comprising a crumb receiving body, a brush rotatably mounted with respect to the body and adapted to throw crumbs therein from a surface to be cleaned, self-contained spring power means for rotation of the brush independently of movement of the sweeper across said surface, winding means for the spring power means, and manually releasable latch means normally locking the power means and brush against rotation, said brush being readily and separately removable from the body for cleaning and having a bearing portion at one end and a first cooperating shaft coupling portion at the other end, the power means having a driving shaft with a second cooperating shaft coupling portion engaging said first coupling portion, and said body having a bearing support movable between retaining and releasing positions with re-

spect to said brush bearing portion, the shaft coupling portions being readily disengaged upon movement of said bearing support to releasing position for removal of the brush.

5. A crumb sweeper comprising a relatively long narrow crumb receiving body provided with a flat scraping edge for engagement with a surface to be cleaned, a relatively long narrow rotary brush mounted in the body for rotation on a pre-determined axis, with the brush having an outer edge parallel to said scraping edge and adjacent thereto, a handle on said body projecting from one end thereof along said pre-determined axis, and spring power means in said handle operatively connected to the brush, said brush having one end removably mounted in the body and its other end supported in detachable driven engagement with a portion of said spring power means, and the body having a retaining member movable between retaining and releasing positions with respect to said one removably mounted brush end.
